UNITED STATES PATENT OFFICE.

GLENN H. CURTISS, OF HAMMONDSPORT, NEW YORK, ASSIGNOR TO CURTISS AERO-PLANE & MOTOR CORPORATION, A CORPORATION OF NEW YORK.

HYDROAEROPLANE.

1,420,609.

Specification of Letters Patent. Patented June 20, 1922.

Application filed August 22, 1911. Serial No. 645,340.

To all whom it may concern:

Be it known that I, GLENN H. CURTISS, a citizen of the United States, residing at Hammondsport, New York, have invented 5 certain new and useful Improvements in Hydroaeroplanes, of which the following is a clear, full, and exact description.

My invention relates to improvements in hydro-aeroplanes, and has reference particularly to a machine adapted to alight on 10 the water and rise therefrom by its own power.

There have been various speculative suggestions of machines for flying from the 15 water into the air and again alighting upon the water; but prior to my invention no one had succeeded in building a successful machine for accomplishing this purpose.

This invention relates to features of construction of the machine and combinations 20 of elements and controlling means, whereby the machine can be laterally balanced and controlled on the water and caused to hydroplane to reduce its resistance on the water, 25 and be flown from the water into the air and again alight upon the water.

My invention will be set forth in the claims.

In the drawings which show the preferred 30 form of my invention,

Fig. 1 is a perspective view from the front, parts having been omitted in order not to complicate the drawings;

Fig. 2 is a side elevation;

35 Figs. 3, 4 and 14 are details of the folding wheel construction;

Fig. 5 is a top plan view of the machine;

Fig. 6 a front view showing the arrangement of the mechanism for operating the 40 ailerons;

Figs. 7 and 8 are rear end side elevations of a socket;

Fig. 9 is a front elevation of a portion of the superposed surfaces;

45 Fig. 10 a plan view of one of the panels;

Fig. 11 a front elevation of a machine having three superposed surfaces; and

Fig. 12 is a sectional detail of Fig. 10 taken on the line X—X.

50 Figs. 13-16 are enlarged details.

The machine shown in the drawings is one constructed so as to be capable of landing and floating on the water and of being driven forward by its own power in contact

with the water, at a speed sufficient to cause 55 the lift of the air to be greater than the weight of the whole machine, in order that the machine may rise out of the water and fly in the air. In the drawings I have shown 60 an aeroplane or heavier-than-air machine provided with floating means to support the same on the water, and other constructions by which this result may be accomplished. The aeroplane proper is substantially the 65 ordinary Curtiss machine which is now well known. It comprises an aeroplane surface sufficient to support the whole machine in the air and which is preferably split up into two superposed areas or surfaces 1 and 2 connected by spacing posts 3 and 4. 5 is a front substantially-horizontal rudder pivoted at 6 to the frame and rockable on its pivot by a manually movable device under the control of the operator, such as a lever 7 located in 75 front of the operator's seat and pivoted at 8 to rock back and forth. 9 is a connecting bar pivoted at its ends to the elevating plane 5 and to the lower end of the said lever 7. 10 and 11 are fixed horizontal surfaces at the 80 rear, and 12, 13 are substantially horizontal elevating rudders pivoted to the fixed surfaces at 14. 15 is a vertical rudder pivoted to the fixed surface. 16, 17 is the bed for the engine 18. This engine may be the well 85 known eight cylinder 50 horsepower four cycle Curtiss engine, the cylinders being arranged in V position with radiator 19, tail shaft 20, and propeller 21 having a radius of 3½ feet and pitch of 6 feet, rotating at 90 about 1200 revolutions per minute. 22 and 23 are substantially flat ailerons located between the surfaces 1 and 2 and are preferably pivoted to the rear posts 4, 4. These ailerons may be thrown in opposite directions by the 95 operator by means which will be hereafter described and which are shown in Fig. 6, in order to restore the equilibrium of the machine in flight through the air. The elevating rudders 5, 12 and 15 serve to direct the 100 course of the machine up or down as desired, or to tilt it up or down on the water and the means by which they may be operated will be more particularly described hereafter.

Carried below the aeroplane surface 2 and 105 fixed thereto by braces 24, 25, 26 is a floating means adapted to support the machine on the water. In the preferred form of my invention shown in the drawings this con-

sists of a single watertight boat 27, one foot deep, two feet wide, and 16 feet long, flat on top and bottom and upwardly-inclined at its forward under surface 28 and downwardly inclined at its rear upper surface 29 to form in intersection with the bottom a transverse edge extending all the way across the boat. The surface 28 and the flat bottom are hydroplaning surfaces and both of them 10 terminate laterally in abruptly turned chine edges. When the machine is at rest on the water the boat is submerged to substantially the water line indicated by the dotted line 30, and preferably extends somewhat forward of the aeroplane proper and to the rear of the propeller 21 and also to the rear of the center of gravity of the machine. It 15 will be obvious that when the machine is at speed on the water the action of the surface 20 of the inclined prow and flat bottom lifts the boat to the top of the water. Furthermore that in accordance with the laws of the hydroplane the region of the center of hydroplane lift lies nearer to the front edge 25 of the surface than to the rear edge, in the usual case one-third its length from the leading edge. The projection of the boat forward of the wings as shown places its central portion opposite the region of the center 30 of aeroplane lift, and therefore its own center of lift in advance thereof. I prefer to divide the floating means into separate compartments by transverse partitions 31 to prevent any water which may leak in from flowing 35 in back and forth in the boat.

In order to prevent either side of the planes from coming in contact with the water during travel through the water, I have provided at each side thereof devices 40 acted on by the rush of water at positive angles of incidence in order to give a lift to either side which may be depressed. These are preferably upwardly inclined devices extending slightly into the water when 45 the machine is at rest, and which when the machine is at full speed barely touch the water, and in the embodiment shown are narrow blades 39 and 40 of flexible wood which, in traveling over the water, stand in 50 the position shown in Fig. 1. If either side of the machine tips downward, the blade on that side touches the water and through the lift exerted by the rush of water straightens up the machine to substantial equilibrium. 55 This operation in the embodiment shown takes place without any necessary action on the part of the operator, and therefore constitutes an automatic stabilizing means. The floats 32 and 33 are preferably pivoted at 60 34 and 35 to the braces 36, 37, and 38 38' are springs normally tending to hold the floats horizontal as shown in Fig. 1. In order that the operator may, if he desires vary the 65 inclination of the floats and blades, I have provided a lever 42 connected to a wire 43

leading to each float, so that by movement of said lever from the position shown in Fig. 2 to that shown in Fig. 1, the floats, and with them the blades, may be inclined upward. Movement of the lever in the reverse direction allows the floats and blades to return to the horizontal position shown in Fig. 2, where they will exert slight head resistance to the rush of air. When the machine is at rest on the water, the floats may be allowed 75 to take the horizontal position and prevent either side of the machine from dipping into the water. When the machine is started, the operator may throw his lever to incline the floats and blades, as shown in Fig. 1, and 80 they will then act as an automatic stabilizing means. When the machine gets into the air the operator causes them to return to the horizontal position.

The inclined portion 28 of the boat is one 85 form of a hydro-surface which is adapted if it should first strike the water as the machine descends to tilt the front of the machine upwardly as it alights on the water, in order that the sudden resistances offered by 90 the water may not cause the machine to dive.

45 and 46 are wheels constituting the preferred form of means for supporting the machine in travel in contact with the earth, if the machine is desired to run over the 95 earth also. They are hung from the machine and project slightly below the lower surface of the boat, as indicated in Fig. 2. In order that they may exert less resistance when the machine is moving through the 100 water, I have provided means under the control of the operator for raising the wheels out of the water when the machine is floating, and for depressing the same at will. In the preferred construction, 47 is 105 a brace pivoted at 48 to the frame of the machine, and 49 is another brace pivoted at 50 to the frame, and at 51 pivoted to a short arm 52. A locking device shown in Figs. 3 and 4 in detail operates to hold the 110 wheels in their depressed position shown in Fig. 1. As shown in Figs. 3 and 4 and 14 the wheel is pivoted to the U-shaped frame 52 having projections 53 pivoted to the U-shaped end 54 of the brace 49. Bent 115 arms 55 fixed to the frame 52 carry pivoted to them at 56 a locking detent 57, which has a catch-nose 58 engaging a bar 59 on the U-shaped frame 54. 60 is a spring normally holding the latch in the position 120 shown in Fig. 4. The preferred mechanism for raising the wheels comprises a slidable rack bar 105 (see Figs. 13 and 14) engaged by a spring-pressed detent 106. 62 is a wire connected to the bar and running to the 125 axle of the wheel, being led over suitable pulleys such as 61. 107 is a foot lever pivoted to the boat at 108 and carrying a spring dog 109; 110 is a spring to draw lever 107 backwards. As the foot lever is recipro- 130

cated it forces the bar 105 downwardly, being held by detent 106 at each reciprocation, drawing on wire 62 and collapsing the frame 47, 49, 52 to the raised position shown 5 in Fig. 14. The holding latch 106 may be tripped by a wire 111 and handle 112 adjacent to the operator's seat. In order to release lock 57 a wire 113 runs therefore to a pulley 114 loose on wire 62. This latter 10 is slack when the wheels are down and locked, and as the slack is taken up it draws on wire 113, unlocking latch 57 just before wire 62 becomes taut. Of course the other wheel is provided with the same construction, the wires 62 of both wheels being connected to rack bar 105. Releasing the detent 106 before the machine comes out 15 of the water allows the weight of the parts and the resistance offered by the water to throw the wheels back to the locked position shown in Figs. 1 and 4. The machine may then travel out of the water onto the land and over the same without the resistance which would be exerted by the boat 20 25 if in contact with the earth.

The elevating rudders 5, 12 and 13 are pivoted on transverse axes 6 and 14. Each 30 of the rear rudders carries a post 63 extending above and below it, and from the upper end of each post a wire 64 leads to the lever 7 below its pivot, and from the lower end of each post 63 a wire 65 leads to the lever 7 above its pivot. Consequently when the lever 7 is pulled backward toward the operator, the connecting bar 9 causes the elevating rudder 5 to be presented to the wind 35 at a positive angle of incidence and both rudders 12 and 13 to be tilted up to a negative angle of incidence. Consequently the action of the air on the rudder 5 tends to 40 elevate the front of the machine, and the action of the air on the rudder 12 and 13 tends to depress the rear of the machine. Obviously movement of lever 7 in the opposite 45 direction has the contrary effect. The rudders 12 and 13 are preferably cut away as shown in Fig. 5, and pivoted between them and to the horizontal fixed surface is a vertical rudder 15 which swings between 50 the rudders 12 and 13. The vertical rudder may be operated from a steering wheel 66 mounted on lever 7 and connected to the vertical rudder by tiller ropes 67, passing up through the hollow lever 7, arm 121 and 55 around said wheel 66 as shown in Fig. 15.

The fixed surfaces 10 and 11 are substantially V-shaped but joined together to provide a fixed pivot for the vertical rudder and are fixed at their rear and immovably 60 held at their apexes by the connecting struts 68 and 69. This construction prevents the "whipping" which might occur if the V-shaped space between them were not provided.

65 The ailerons 22, 23 are preferably located

substantially midway between the surfaces 1 and 2, and therefore are not so much affected by the deflection of the air currents caused by the impingement of the air on said surfaces 1 and 2, as said ailerons would 70 be if they were hung directly to the rear edge of said surfaces. In the present embodiment I have shown them as pivoted to the rear posts, but this location is not essential, although such location is preferable 75 as the wedging effect of the air is less at this position than would be the case if they were moved forward and pivoted to the front posts. I, however, do not desire to be limited to any particular location of the 80 ailerons, or to the use of ailerons as distinguished from other known lateral balancing means.

In order to provide means under the control of the operator for throwing these ailerons to opposite angles of incidence, I have provided connections therefrom by which the operator may tilt them in either direction, and preferably simultaneously in opposition directions. This in the embodiment 90 shown comprises a laterally movable device, such as a shoulder frame 70, pivoted to the seat 71 by connecting bars 115, 116, 117 by which the frame may be moved from side to side, and carrying pivoted to it a rocking 95 arm 72 with wires or ropes 73, 74 and 75, 76, said wires being attached to the projections or posts 77, 78 on the ailerons. It will be obvious that moving the shoulder frame in either lateral direction will tilt the ailerons 100 in opposite directions.

The ailerons, as well as the rear rudders 12 and 13, are stiffened by wires running from each end of the posts or projections thereon to the corners of said surfaces. In 105 order to allow the control mechanism which operates the ailerons and vertical and horizontal rudders to be shifted to or from a passenger I have provided a construction by which this may be done instantaneously 110 when in flight. In the preferred construction illustrated the passenger is provided with a seat 118 and laterally movable shoulder frame 119 similar to that on seat 71, but normally unconnected to frame 70. In order 115 to connect the frame 119 to the aileron wires so that they may be operated from frame 119 I have provided a latch 120 which may be snapped over frame 70 as shown in dotted lines. This may be done almost instantaneously, and the passenger may then operate the ailerons. In order to pass the control for the vertical and horizontal rudders to the passenger I prefer to rotatably mount the steering wheel 66 within a fork 66' on 120 arm 121 pivoted to levers 7 at 122 so that the wheel may be passed across from one seat to the other. It may be locked in either position by a quadrant 123 fixed to lever 7 and a spring latch 124 on arm 121. This con- 130

struction has been used with perfect success in transferring control of the machine from one operator to another during free flight in the air. Obviously the mode of operation 5 of the machine is precisely the same from either seat.

In order to provide a construction of the surfaces 1 and 2 which will allow the 10 same to be inexpensively constructed and easily set up and taken down, I prefer to build said surfaces of similar panels, with 15 sockets by which a panel may be easily fastened to or detached from an adjacent panel, and the sockets provided with means for attaching the spacing posts to them in order 20 that any number of surfaces may be easily superposed, and in fact any form of machine made without materially weakening the construction. The machine shown is 25 built up of separate panels, one of which is shown in Fig. 10, comprising a frame having a front bar 79, a rear bar 80, side bars 81 and 82 and ribs 83, 84. Cloth or any other equivalent air-resisting material 85 is stretched over top and bottom of the frame and may be tacked to the bars and ribs. 125, 126 are strengthening braces to prevent lateral distortion.

In order to detachably hold the panels, I 30 have provided sockets such as shown in Figs. 7, 8 and 9, made of metal bent into a substantial U-shape. As seen in Fig. 9, the panel 87 is slipped laterally into the socket 88 and fastened by passing the bolt 89 through the socket and side bar. The panel 90 is slipped into the similar socket 91 and similarly fastened. The spacing post 4 is slipped into the sockets 91 and 92, and the 35 diagonal trussing wires 93, 94 attached to the diagonal ears of the socket. If two additional panels are to be provided in the same plane as the other panels, the similar panels 95, 96 may be slipped into the open ends of the sockets and similarly fastened 40 and trussed by the wires 97, 98. The sockets 125 at the rear may be the same, or, if it is desired to extend the surfaces beyond the rear posts, they may be made in two parts by merely cutting off the connecting metal 45 as shown by the dotted line y—y in Fig. 8.

If it is desired to make a machine of three superposed surfaces, or to add or omit any desired panels, it is very easy to do so. For example as shown in Fig. 11, an additional surface 100 has been added above the other two by adding five similar panels with sockets and posts and trussing wires. With such construction the machine may be easily assembled and knocked down, and the cost 60 of construction is materially reduced.

Assuming the machine to be resting on the water, the operator releases his lever allowing the floats 32 and 33 to come to the horizontal position so that they support 65 either side of the machine which tips down-

wardly. After raising the wheels, the engine is started, which will drive the machine through the water, and as it starts the operator pulls on the lever, inclining the balancing blades to the position shown in Fig. 1, and, as the boat lifts somewhat as the speed increases, they barely touch the water as long as the machine is in balance laterally. The rush of the water against them exerts a lift, and depression of one side of the machine causes the blade on that side to enter the water to an extent proportional to the amount of depression and the other blade will rise out of the water. The one in the water exerts a lift due to water-rush against the inclined surface which will restore equilibrium, and the lift decreases as equilibrium is approached. The machine will therefore automatically be kept substantially horizontal. In making a turn to the left or the right on the water, the effect of the rear vertical steering rudder may be supplemented by causing the one or the other balancing blade to exert a drag on the side toward which the turn is to be made. This may be done by depressing either side of the machine by the use of the ailerons. This will cause the machine to tip laterally and the blade on the depressed side to dip into the water to an abnormal extent, and help to turn the machine toward that side. The action of the inclined surface 28 of the boat causes the machine to tilt upward somewhat, and the flat under-surface of the boat and the downwardly-inclined surface 29 thereon causes the water to be left in a not seriously disturbed condition and prevents the machine from burying, that is, tipping unduly downward at the rear. When the speed of the machine over the water is sufficient, the operator pulls the lever 7 backward, which tilts the front elevating rudder to a positive angle of incidence, and the two rear elevating rudders to negative angles of incidence, and the machine rises out of the water. The operator then releases the lever 61, which allows the floats 32, 33 and blades to take the horizontal position where they offer the least resistance to the atmosphere. In descending to alight on the water, the operator shuts off his engine if desired, and glides downward to the water, at the same time pulling on his lever 42 to incline the balancing blades. The inclined hydro-surface 28, if it first strikes the water serves to turn the machine upwardly from its gliding course, so that it will not topple over forward and tend to dive. As it runs forward on the water, the blades keep it in substantial equilibrium. If it is desired to run out onto a beach, for example, the engine may be started or allowed to continue to run, and as the shore is approached the operator releases detent 106 which allows the wheels to drop back to their position shown in Fig. 2.

and as they project slightly below the bottom of the boat he may run up on the land. The machine may either rise from the land or water as desired.

5 I am aware that various modifications may be made in my invention without departing from the spirit of the claims, and I therefore do not desire to be limited to the preferred embodiments herein shown in the 10 drawings.

What I claim is:

1. A heavier-than-air flying machine having a water-borne structure adapted to support the machine on and travel in contact 15 with the water, said machine having toward each lateral end thereof a flexible blade extending toward the water and adapted to be flexed backward and upward by the rush of water as the machine loses its lateral equilibrium.

2. A heavier-than-air flying machine adapted to rise from the water by its own power comprising an aeroplane, a boat-like structure below said aeroplane constituting 25 the main supporting element when the machine is on the water and a pivoted float of relatively small supporting power below and at each side of the aeroplane, and means under the control of the operator to vary the 30 inclination of said floats simultaneously in the same direction at will.

3. In a machine of the character described, an aeroplane adapted to be acted on by the air to exert a lifting effect, a single 35 narrow boat having a substantially flat and upwardly inclined forward hydroplaning under-surface adapted to support the whole machine when it rests on the water and (except for the lift of said aeroplane) constituting 40 substantially the entire supporting element so long as the machine is traveling in contact with the water, a hydro-surface toward each lateral end of the machine and extending toward the water, said hydro-surfaces 45 being so arranged that when the machine is traveling at full speed with said boat in contact with the water, said hydro-surfaces are substantially out of the water but adapted to engage the water and, 50 through the lifting effect of the rush of water against said surfaces, automatically to balance the machine when either side thereof becomes depressed, said surfaces being of slight supporting power compared with that 55 of said floating means.

4. In a machine of the character described, an aeroplane adapted to be acted on by the air to exert a lifting effect, floating means below the same adapted to support substantially 60 the whole machine when standing on the water and (except for the lift of said aeroplane) constituting substantially the entire supporting element so long as the machine is traveling in contact with the water, 65 a float and extending below it a hydro-surf-

face toward each lateral end of the machine, said hydro-surfaces extending to the water when the machine is in equilibrium and moving slowly, said hydro-surfaces being so arranged that when the machine is traveling 70 at full speed in contact with the water, said hydro-surfaces are substantially out of the water but adapted to engage the water and, through the lifting effect of the rush of water against said surfaces, automatically to 75 balance the machine when either side thereof becomes depressed, said surfaces being of slight supporting power compared with that of said floating means.

5. In a machine of the character described, 80 an aeroplane adapted to be acted on by the air to exert a lifting effect, floating means below the same adapted to support the whole machine when at rest on the water and (except for the lift of said aeroplane) constituting 85 substantially the entire supporting element so long as the machine is traveling in contact with the water, a relatively small float at each side of the machine substantially without buoyant effect while the machine is traveling upon the water, a hydro-surface outside of said floating means and toward each lateral end of the machine, located substantially only at the center of gravity of the whole machine and extending 90 toward the water, and adapted to automatically balance the machine when either side 95 becomes depressed.

6. A heavier-than-air flying machine having an aeroplane, and a main water-borne 100 structure adapted to travel in contact with and be supported by the water and constituting substantially the entire supporting element when the machine is speeding in contact with the water, an inclined hydro-surface 105 toward each lateral end of the aeroplane and acted on by the rush of water, said aeroplane having a movable surface at each side under control of the operator to create a difference of air lift whereby the operator 110 may depress either side of the machine when traveling in contact with the water and thereby force the hydro-surface on that side deeper into the water to create a drag on that side of the machine to aid in steering the same, and correspondingly raise the hydro-surface on the elevated side so that it is 115 substantially out of the water before the wing tip on the depressed side comes in contact with the water.

7. In a machine of the character described, 120 an aeroplane adapted to be acted on by the air to exert a lifting effect, floating means below the same adapted to support substantially the whole machine when it stands on the water and (except for the lift of said aeroplane) constituting substantially the entire supporting element so long as the machine is traveling in contact with the water, a relatively small buoyant float under- 130

- neath and toward each lateral end of the machine and of slight supporting power compared with that of said floating means, each of said floats having a surface inclined 5 downwardly and rearwardly toward the water and adapted to be acted on by the rush of water, said floats being so arranged that when the machine is traveling at full speed in contact with the water they are substantially 10 out of the water but adapted to engage the water with their inclined surfaces if either side of the machine becomes unduly depressed.
8. In a machine of the character described, 15 an aeroplane adapted to be acted on by the air to exert a lifting effect, floating means below the same adapted to support substantially the whole machine when it is standing on the water and (except for the lift of 20 said aeroplane) constituting substantially the entire supporting element so long as the machine is standing upon or traveling in contact with the water, a hydro-surface outside of said floating means and toward each 25 lateral end of the machine, located substantially only opposite the center of gravity of the whole machine, extending down toward the water but terminating above the lower surface of said floating means, and adapted 30 automatically to balance the machine when either side becomes depressed.
9. In a machine of the character described, 35 an aeroplane adapted to be acted on by the air to exert a lifting effect, a substantially flat-bottomed boat-like structure, below the same located close to the longitudinal axis of the machine and adapted to support the whole machine in unstable lateral equilibrium when at rest on the water and (except 40 for the lift of said aeroplane) constituting substantially the entire supporting element while the machine is standing and at all speeds so long as the machine is traveling in contact with the water, and toward each 45 lateral end of the aeroplane a float of small buoyancy compared with that of the said boat-like structure, said floats being substantially above the level of the bottom of said boat and each having a surface downwardly and rearwardly inclined and adapted 50 to be acted on by the rush of water when the machine loses its lateral equilibrium.
10. In a machine of the character described, 55 an aeroplane having below and substantially central of it a hydroplane surface adapted (aided by the lift of said aeroplane) to support the whole machine at substantially a flying angle of incidence when speeding in contact with the water, and toward 60 each lateral end of the aeroplane and below it a buoyant float having a hydro surface inclined upwardly toward the front, the major portion of said floats being higher than the water line of said first hydroplane surface, whereby when the machine is speeding 65 on the water said floats are substantially out of the water.
11. In a machine of the character described, 70 an aeroplane, a boat-like structure below the same adapted to support the machine on and travel in contact with the water, a rearwardly inclined hydro surface toward each lateral end of the aeroplane and below the same adapted to be acted on by the rush of water when the machine loses 75 its lateral equilibrium, said machine being without any material water-resistant surfaces lower than the water line of said boat and aft of the body of the boat, whereby the machine may rock upward at the front 80 and rise from the water without being materially resisted at the rear.
12. A hydro-aero-machine comprising a main aeroplane supporting surface, lateral stabilizing aeroplane surfaces to create a 85 difference of lift, a main water-borne central boat structure adapted to support the entire machine when on the water, and except for the aeroplane lift, constituting substantially the entire supporting element at 90 all speeds so long as the boat structure is traveling in contact with the water, relatively small horizontal water balancing floats located below the supporting plane and beyond each side of said boat structure, 95 said floats being located above the level of the boat bottom and provided with surfaces inclined downwardly and rearwardly, adapted to be acted upon by the rush of water when the machine loses its lateral 100 equilibrium, and means for operating the stabilizing surfaces to create a difference of air lift.
13. A hydro-aero-machine comprising one or more aeroplane supporting surfaces for 105 lifting the machine from the water and supporting it in the air, a water-borne structure adapted, except for the aeroplane lift, to support substantially the entire machine at all speeds on the water, and adapted to hydroplane so as to assist in lifting the machine to the surface of the water and permit the machine to be lifted from the water by the aeroplane lift, aerial propulsion means adapted to drive the machine forward at 110 sufficient speed for the air lift on said aeroplane surface to lift the machine out of the water, a lateral stabilizing device toward each lateral end of the machine adapted to 115 be acted upon by the water when the machine is tipped laterally thereby automatically to balance the machine on the water when either side becomes depressed, lateral stabilizing aeroplane surfaces and means operating same to assist in controlling the 120 machine, and one or more elevator aeroplane surfaces adapted to assist in changing the angle of incidence of the machine while 125 running on the water and while in the air.
14. A hydro-aero-machine comprising one 130

or more aeroplane supporting surfaces for lifting the machine from the water and supporting it in the air, a water-borne central boat structure adapted, except for the aero-
 5 plane lift, to support substantially the entire machine at all speeds on the water and having a downwardly and rearwardly inclined forward bottom surface to assist in getting the machine up on the water, and
 10 thence a more horizontal hydro-planing bottom portion terminating in a broad transverse edge, and adapted to enable the machine to hydroplane up in the water, be rocked longitudinally by manipulation of
 15 elevator surfaces, and with the assistance of the aeroplane surface to be lifted up on to the water to reduce head resistance and to be lifted from the water by the air lift, said aeroplane surfaces being positioned on the
 20 boat structure to produce a proper lifting effect when the machine is hydroplaning, relatively small lateral balancing buoyant means located beyond each side of the boat structure and above the bottom of the boat
 25 structure and adapted to be acted upon by the water when the machine becomes depressed on one side, to automatically assist in balancing the machine while running on the water, aerial propulsion means adapted
 30 to drive the machine forward at sufficient speed for the air lift on said aeroplane surface to lift the machine out of the water, lateral stabilizing aeroplane surfaces and means operating same to enable the machine
 35 to be rocked laterally while on the water and assist in steering it, and to assist in controlling it in the air, and one or more elevator aeroplane surfaces adapted to assist in changing the angle of incidence of the
 40 machine while traveling on the water and while in the air.

15. In a machine of the character described, an aeroplane adapted to be acted upon by the air to exert a lifting effect, floating means below the aeroplane adapted to support substantially the whole machine when it rests on the water and, except for the lift of the aeroplane, constituting substantially the entire supporting means so long as the
 45 machine is traveling in contact with the water, and a relatively small float at each side of the machine adapted to automatically balance the machine by engagement with the water should either side thereof become depressed.

16. A heavier-than-air flying machine adapted to rise from the water by its own power comprising an aeroplane, floating means constituting, except for the aeroplane lift, the main supporting element so long as the machine is traveling on the water, a hydro surface at each side of the floating means, each hydro surface being capable of adjustment while the machine is in operation, to the end that the resistance which

such surfaces offer to the air during flight may be lessened, said hydro surfaces during operation of the machine on the water providing an automatic water-balancing means.

70

17. A device of the character described having a buoyant hull-like body portion adapted to traverse the water, and except for the aeroplane lift adapted to be substantially the entire supporting element at all speeds so long as the body portion is in contact with the water, planes extended from opposite sides of said body portion having inovable parts and operable to sustain the structure during aerial flight and to assist in balancing the same during travel over the water, driven propelling means, and buoyant bodies extended at opposite sides of the body portion operable by contact with the water to assist in balancing the structure.

85

18. A heavier-than-air flying machine having an aeroplane, and a water-borne structure adapted except for the aeroplane lift to be substantially the entire supporting element of the machine at all speeds on the water, said machine having in the direction of each lateral end thereof a surface extending toward the water and adapted to be acted upon by the rush of water as the machine loses its lateral equilibrium.

90

19. A hydro-aero-machine having an aeroplane adapted to be acted on by the air to exert a lifting effect, floating means below the same adapted to support the whole machine when it rests on the water and except for the lift of said aeroplane constituting substantially the entire supporting element so long as the machine is traveling in contact with the water, a surface at a positive angle of incidence to the water in the direction of each lateral end of the machine, said surfaces being so arranged that when the machine is traveling at full speed in contact with the water said surfaces are substantially out of the water but adapted to engage the water and through the lifting effect of the rush of water against said surfaces, automatically to balance the machine when either side thereof becomes depressed.

105

20. In a machine of the character described, an aeroplane adapted to support the whole machine in the air, lateral stabilizing surfaces to create a difference of air lift, a buoyant structure adapted to support the entire machine when at rest on the water and except for the lift of said aeroplane constituting substantially the sole supporting element so long as said machine is traveling in contact with the water, said buoyant structure having an upwardly inclined forward hydro-surface acted on by the rush of water and a substantially flat bottom, said aeroplane being so attached to said

- buoyant structure that when it is speeding in contact with the water said aeroplane is maintained at substantially a flying angle of incidence, whereby the machine rises to 5 the top of the water and the head resistance of the water is decreased, and a propeller operating on the air to drive the whole machine forward until the air lift on said aeroplane raises the machine out of the water.
- 10 21. A hydro-aero machine having a main aeroplane supporting surface, a water borne central boat structure adapted to support the entire machine when on the water, and except for the aeroplane lift, constituting 15 substantially the entire supporting element at all speeds so long as the boat structure is traveling in contact with the water, and lateral water stabilizing surfaces to create a difference of lift.
- 10 22. A hydro-aero-machine having a main aeroplane supporting surface, lateral stabilizing aeroplane surfaces to create a difference of lift, a main water borne central boat structure adapted to support the entire 25 machine when on the water, and except for the aeroplane lift, constituting substantially the entire supporting element at all speeds so long as the boat structure is traveling in contact with the water, means for operating the 30 stabilizing surfaces to create a difference of air lift, and said boat structure having a relatively broad forward under-surface and lateral water balancing means.
23. A hydro-aero-machine having a main aeroplane supporting surface, lateral stabilizing aeroplane surfaces to create a difference of lift, a main water borne central boat structure adapted to support the entire machine when on the water and except for the 40 aeroplane lift, constituting substantially the entire supporting element at all speeds so long as the boat structure is traveling in contact with the water, and means for operating the stabilizing surfaces to create a difference 45 of air lift, whereby said machine may be turned while on the water, and lateral water balancing means.
24. A hydro-aero-machine having a main aeroplane supporting surface, lateral stabilizing aeroplane surfaces to create a difference of lift, a main water borne central boat structure adapted to support the entire machine when on the water, and except for the aeroplane lift, constituting substantially the 50 entire supporting element at all speeds so long as the boat structure is traveling in

contact with the water, means for operating the stabilizing surfaces to create a difference of air lift, and floats being adapted to be secured in an adjusted position.

25. In a machine adapted to fly in the air from the water while running at speed on the water, the combination of a main aeroplane supporting surface acted upon by the air so as to tend to lift the machine to lessen 60 displacement of the machine when running at speed on the water, one or more elevator air planes to assist in changing the angle of incidence of the machine while running at speed on the water, a main water-borne central boat structure adapted to support substantially the entire machine on the water, and except for the aeroplane lift, constituting substantially the entire supporting element 65 at all speeds of the boat structure on the water, relatively small horizontal balancing water floats located below the supporting plane and beyond each side of said boat structure, said floats being located above the level of the boat bottom and provided with surfaces inclined downwardly and rearwardly, adapted to be acted upon by the rush of water when the machine loses its lateral equilibrium, means for operating the elevators to vary the angle of incidence 70 of the machine on the water, and an air propeller with means for driving the same to propel the boat at speed on the water.

26. In a machine adapted to fly in the air from the water while running at speed on the water, the combination of a main aeroplane lift surface, a main water-borne central boat structure adapted, except for the aeroplane lift, to support substantially the entire machine at all speeds so long as the 90 boat structure is traveling in contact with the water, relatively small horizontal balancing floats located below the supporting plane and beyond each side of said boat structure, said floats being located above the 95 level of the boat bottom and provided with surfaces inclined downwardly and rearwardly adapted to be acted upon by the rush of water when the machine loses its lateral equilibrium.

Signed at Hammondsport, N. Y., this 11th day of August, 1911.
